UNITED STATES PATENT OFFICE.

EDWARD BUTLER, OF ATLANTIC, IOWA, ASSIGNOR OF ONE HALF TO THEO. G. STEINKE, OF SAME PLACE.

STOVE.

SPECIFICATION forming part of Letters Patent No. 359,532, dated March 15, 1887.

Application filed December 4, 1885. Serial No. 184,717. (No model.)

To all whom it may concern:

Be it known that I, EDWARD BUTLER, a citizen of the United States, residing at the city of Atlantic, in the county of Cass and State of Iowa, have invented a new and useful Improvement in Stoves, of which the following is a specification.

My invention relates to improvements in that class of stoves known as "hot-air stoves;" and the objects of my improvements are to keep the coal in the magazine of a self-feeding stove cool by means of introducing and circulating cool air around the magazine; also, to utilize the heat in warming the room that 15 the air which surrounds the magazine receives. I attain these objects by the stove or heater illustrated in the accompanying drawings, in which—

Figure 1 is a vertical central section of the 20 stove from front to rear. Fig. 2 is a cross-section of the stove on the line $x-x$, (indicated in Fig. 1.) Fig. 3 is a detailed view of the top plate of the stove. Fig. 4 is a detailed view of the bottom plate of the stove.

Similar letters refer to similar parts throughout the several views.

The bottom plate, D, has the apertures or slots $n-n-n$, and between the apertures the supports $t-t$, which connect with and support 30 the rim k , upon which the outer case or drum of the stove rests.

The top plate, E, has the apertures $d-d$, for the escape of the air that circulates between the drums a and e . It also has an aperture for 35 the insertion of the cylinder s , which surrounds and supports the magazine. The cylinder s is secured to the plate E. In the bottom of the cylinder s is an aperture of sufficient size to allow the magazine R to project 40 through. The top of the cylinder is open, but has arms $v-v$, reaching inward from the inner circumference of the cylinder at its top, and of sufficient length to touch the magazine on its outward circumference. The cylinder also has 45 perforations near its base to admit the tubes $i-i$.

The magazine R, which holds the coal to feed the stove, has a smaller diameter than the cylinder s , and it has a flange, b , cast upon its outer circumference near its base.

50 The magazine R is within the cylinder s , and projects through and below it. The flange

b rests upon the bottom of the cylinder s and supports the magazine. Between the magazine R and the cylinder s is the air space or chamber y , open at the top and closed at the bottom, and having opening into it the tubes $i-i$.

The stove has two cases or drums, a and e , the outer drum, a , being considerably larger in diameter than the inner drum, e . Between the drums is the air-passage w . The outer drum, a , rests upon the rim k of the plate D. The inner drum, e , rests upon the plate D inside of the apertures $n-n-n$. The tubes $i-i$ lead from the chamber y through the inner drum, e , thence downward between the drums a and e , and 65 through the plate D. There can be one or more of the tubes $i-i$ used in the construction of the stove, and the tubes $i-i$ can be made to pass down through the chamber C and through the plate D without passing through the inner drum, e .

P is the fire-pot, and C the smoke-chamber, of the stove. The smoke passes from the chamber C through the pipe h into the escape-pipe o , except when the pipe h is closed by a 75 damper. Then the smoke passes into the pipe o through the pipe m . The stove has the ordinary opening to admit the air to supply the oxygen for combustion.

It is evident that when a fire is made in the 80 stove the inner drum, e , will become hot and heat the air in the passage w , causing it to rise and escape into the room through the apertures $d-d$ of the plate E. At the same time the cold air will enter through the apertures $n-n-n$ into the passage w . It is also apparent that the cylinder s will become hot and heat the air in the chamber y , causing it to rise and pass into the room, and at the same time the cold air will enter the tubes $i-i$ at 85 their lower ends and pass through the tubes into the chamber y , thus keeping the magazine cool and warming the room.

The apertures $d-d$, which are over the air-passage w , can be closed in any convenient 90 manner and the circulation of the air between the drums checked without stopping the circulation through the tubes $i-i$.

Having described my invention, what I claim as new, and desire to secure by Letters Patent, 95 is—

1. The combination of the inner drum, the

smoke-chamber having in open communication therewith a fire-pot, the magazine to hold the fuel and deliver it to the fire-pot, the cylinder which surrounds the magazine, and 5 which is itself surrounded throughout its entire length by the smoke-chamber, the air-chamber between the magazine and cylinder, the air-tubes which extend upward from the base of the stove below the bottom of the fire-pot 10 and pass through the walls of the cylinder *s* and open into the air-chamber *y*, the perforated top plate, and the perforated bottom plate, all substantially as described and shown.

2. A stove consisting of an outer and inner 15 drum, an air-passage between said drums, a smoke-chamber having outlets for the escape of the smoke and having in open communica-

tion therewith an ordinary fire-pot, a magazine to hold the fuel and deliver it into the fire-pot, a cylinder which surrounds the magazine, 20 a chamber, *y*, between the magazine and cylinder, the tubes extending upward from the base of the stove between the lower and middle portions of the drums, thence turning and passing through the inner drum and through 25 the walls of the cylinder, and opening into the chamber between the cylinder and magazine, a perforated top plate, and a perforated bottom plate, all combined substantially as described.

EDWARD BUTLER.
